UNITED STATES PATENT OFFICE.

VINCENT FERRARA, OF WATERTOWN, SOUTH DAKOTA.

APPARATUS FOR DRYING CLOTHES.

Application filed December 14, 1921. Serial No. 522,326.

To all whom it may concern:

Be it known that I, VINCENT FERRARA, a citizen of the United States, residing at Watertown, in the county of Codington and 5 State of South Dakota, have invented certain new and useful Improvements in Apparatus for Drying Clothes, of which the following is a specification, reference being had therein to the accompanying drawings.

10 This invention relates to a clothes dryer, and the object of the invention is the construction of a simple and efficient clothes drier, especially designed to dry clothes that have been dry-cleaned by the French method, 15 or other dry-cleaning methods, and, in particular, is efficient where the clothes have been cleaned with the use of gasoline or benzine.

With the foregoing and other objects in view, my invention comprises certain novel 20 combinations, constructions and arrangements of parts as will be hereinafter described, illustrated in the accompanying drawings, and more particularly pointed out in the appended claims.

25 In the drawings:

Figure 1 is a longitudinal, sectional view of an apparatus constructed in accordance with the present invention.

Figure 2 is a sectional view, taken on line 30 2—2, Fig. 1, and looking in the direction of the arrows.

Figure 3 is a fragmentary, perspective view of the discharge pipe.

Figure 4 is a perspective view of the metal sheet.

Referring to the drawings by numerals, 1 designates a compartment, such as a room, which is provided in its top with an outlet 2, and in the bottom with an outlet 3.

40 A steam pipe 4 extends into the top portion of the room or compartment 1 and is formed into coils 5. Above the coils 5, of pipe 4, is placed a sheet 6, formed of metal, and this sheet is suspended immediately 45 above the pipe, preferably by means of angle brackets 7, which brackets 7 are not only secured to the top of the sheet 6 but are also fastened to the under face of the top of the room or compartment 1.

50 A blower 8 is positioned close to the top of the room or compartment 1, and this blower 8 is connected by pipe 9 to the discharge pipe 10. This discharge pipe 10 is provided with a longitudinally extending 55 slot 11 that extends the entire length of the pipe and is adapted to direct air, under

pressure, against the coils 5 and sheet 6; the air discharged through pipe 10 will be heated by steam pipe, and, by reason of the sheet 6 will be deflected or forced down against 60 the clothes suspended in the room or compartment. The clothes or suits may be suspended from poles 12, and as the clothes are usually more heavily padded at the top than at the bottom, the air will strike against the 65 clothes with more force at the top, tending to dry the clothes evenly. The air from blower 8 is pure and clean and by forcing the air into the room or compartment while discharging the same against the clothes, the 70 lighter vapors from the clothes that are being dried, will rise to the top of the room or compartment and pass out of the outlet 2, whereas the heavier odors or fumes will move to the bottom of the room or compartment 75 and will pass out at the outlet 3.

I know from actual experience that clothes dried by my apparatus will come out from the drier absolutely without odor. In the structure herein described, the positive flow 80 of clean and fresh air in the drier is obtained, which air is immediately heated. The air is forced into the clothes where it removes the gases, vapors, odors and moisture, and then these gases, or vapors allowed to escape from the room or compartment as soon as released 85 from the clothes without being forced through the clothes again.

While I have described the preferred embodiment of my invention, and have illustrated the same in the accompanying drawings, certain minor changes or alterations may appear to one skilled in the art to which this invention relates, during the extensive manufacture of the same and I, therefore, 90 reserve the right to make such alterations or changes as shall fairly fall within the scope of the appended claims.

What I claim is:

1. In an apparatus of the class described, 100 the combination of a compartment provided with an outlet in its top and an outlet in its bottom, a heating pipe extending into said compartment, a sheet within the compartment above the heating pipe, an air discharge pipe in the compartment under the heating pipe and sheet, and means for suspending clothes in the compartment under the heating pipe and the sheet.

2. In an apparatus of the class described, 110 the combination of a compartment having a discharge opening in its top and a dis-

- charge opening in its bottom, a steam pipe extending through one end of the compartment and formed into coils at the top of the compartment, a metal sheet above the coils
- 5 in the compartment, angle brackets fastened to the sheet and also fastened to the top of the compartment, a discharge pipe in said compartment under the coils and the sheet, said discharge pipe provided near its top
- 10 with a slot extending the length of the pipe, and means for suspending clothes under the discharge pipe, coils and sheet, substantially as shown and described.
3. In an apparatus of the class described,
- 15 the combination of a compartment provided with outlets, clothes supporting means in the compartment between said outlets, a deflecting sheet in the compartment above said clothes supporting means, and means in the
- 20 compartment for supplying heated air against the sheet for directing the same around said clothes supporting means.
4. In an apparatus of the class described, the combination with a compartment, of a
- 25 heating pipe in said compartment, a deflecting sheet above the heating pipe, a discharge pipe with a slot discharging air against the heating pipe and the sheet, and clothes supporting means within the compartment.
- 30 5. In an apparatus of the class described, the combination of a compartment having discharge means, a steam pipe extending through one end of the compartment and formed into coils at the top of the compartment, a metal sheet above the coils in the
- 35 compartment, angle brackets fastened to the sheet and also fastened to the top of the compartment, a discharge pipe in said compartment under the coils and the sheet, said discharge pipe provided near its top with a
- 40 slot extending the length of the pipe, and means for suspending clothes under the discharge pipe, coils and sheet, as and for the purposes set forth.
6. In an apparatus of the class described,
- 45 the combination of a compartment having discharge means, a steam pipe extending into said compartment and formed into coils at the top of the compartment, a deflector sheet suspended above the coils in the compartment, a discharge pipe in said compartment at one end thereof and extending under and transversely to said coils, said discharge pipe provided in its upper portion with a slot
- 50 extending longitudinally thereof, and means for suspending clothes under the discharge pipe, coils and sheet, as and for the purposes set forth.
- In testimony whereof I hereunto affix my signature.

VINCENT FERRARA.
